UNITED STATES PATENT OFFICE.

MENDEL KAPILIAN, OF NEW YORK, N. Y., ASSIGNOR TO HERMAN BAUER, OF NEW YORK, N. Y.

BUTTON-SECURING MEANS.

Application filed March 31, 1927. Serial No. 180,006.

This invention relates to improvements in button securing means and more particularly to means for securing a button to a fur or fabric coat in a firm and substantial manner.

One of the objects of the present invention is to provide an improved button fastening device particularly adapted for use on coats of fur or fabric which eliminates the necessity of sewing on the button or using tape for holding the same in place. As is well known to those familiar with the art, it is extremely difficult to secure buttons to fur coats without danger of them tearing loose and also tearing the fur as well. There is accordingly provided by the present invention a simple and practical device which will permit the button to be easily and quickly attached to the coat and at the same time provide a sufficiently large backing to prevent the button from being torn loose with the consequent danger of damage to the material.

A further object is to provide a button attaching or securing means, which means may be inexpensively manufactured, and involve relatively few parts which may be easily assembled.

A further object is to provide an attachment for buttons adapted for use with most of the different types of buttons now in use and which may be applied to such buttons without the use of special tools either by the maker of the coat or the subsequent user.

Other objects will be in part obvious and in part hereinafter pointed out in connection with the accompanying sheet of drawings illustrating one of various possible embodiments of the invention, and in the several views of which corresponding parts are indicated by similar reference characters.

In these drawings—

Fig. 1 is a general view showing the attachment in open position.

Fig. 2 is a sectional view showing the button applied to a piece of fur or fabric indicating the garment to which the button is to be applied.

Fig. 3 is a view similar to Fig. 1 showing the parts in closed position.

Figs. 4 and 5 are detail sectional views.

Referring now to the drawings in detail and particularly Fig. 1, 10 and 11 indicate

two similarly shaped, relatively flat, sheet metal members substantially semi-circular in shape with a maximum length of approximately one inch. These two members are hinged together at one end by means of a pin or preferably a tubular rivet 12 as shown in detail in Fig. 5. Each of these parts are provided along their straight edges with indentations 13 and 14 separated by a protection or tongue 15 and at their ends, opposite the pin or rivet 12, with coacting latch members. Of course, any desired form of latch may be used but for inexpensiveness and convenience in manufacture, it is preferred to provide the part 10, for example, with an opening 16 adapted to coact with a punched-up lug 17 as shown in detail in Fig. 4.

Referring to Fig. 2, there is indicated a button 18 provided with a shank 20. This shank 20 is usually of circular shape and formed of wire, for example, the ends of which wire are firmly secured or imbedded in the material constituting the body of the button.

When the parts are assembled, a small hole is punched thru the fur indicated at 21, and the shank 20 is passed therethru. The securing plate, Fig. 1, is then placed on the opposite side of the fur in open position and moved to the position shown in Fig. 3, whereupon both coacting tongues 15 pass thru the opening in the shank 20, and the hole 16 snaps over the punched-up lug 17, thus latching or holding the parts firmly in secured position. By having two tongues 15, one overlapping the other, as shown in Fig. 3, the eye of the shank 20 is substantially filled, thus preventing a feeling of looseness to the button when it is in secured position, and adding further strength in accomplishing the desired object. The combined parts 10 and 11 are of sufficient area to absorb any strain exerted upon the button and transmit the same over a relatively large area, thereby eliminating, to a large degree at least, any possibility of the button tearing loose when subjected to ordinary usage.

By having the parts similarly shaped whereby they cooperate, one with another, and with the shank of the button, the cost of manufacture is materially reduced, inasmuch as the same machine will manufacture

both parts except for the minor operation of forming the hole 16 on one and the lug 17 on the other. The rivet may be very easily inserted thru the registering openings thereby to hold the parts in assembled relation yet permit them to turn freely with respect to each other.

It will be noted particularly that no special tools are required for applying the attaching device to the button and this operation may be easily and quickly done by hand, either by the manufacturer of the coat or a subsequent user.

From the above, it will be seen that the present invention provides a simple and practical button securing device suitable for use with most of the buttons now in general use in the trade, which device may be inexpensively manufactured, assembled and applied.

I claim:

1. An article of manufacture of the character described, comprising two mating plates pivotally connected near one end and having a latch connection near the other end, and cooperating indentation and a tongue on each of said plates adapted to engage the shank of a button.

2. An article of manufacture of the character described, comprising two semi-circular plates pivotally connected near their ends, and latch mechanism near their opposite ends, the adjacent surfaces of said plates being provided with means adapted to engage in and cooperate with the shank of a button.

3. In combination with a button having a shank, a securing means adapted to cooperate therewith comprising two relatively movable members, each provided with means adapted to engage in and cooperate with said shank.

4. In combination with a button having a shank forming an eye, a securing means adapted to cooperate therewith comprising two relatively movable members, each provided with means adapted to cooperate with said shank, said means including a projection

on each member adapted to engage in the eye of the shank. 50

5. In combination with a button having the usual shank forming an eye, a securing means adapted to cooperate with said shank and on the opposite side of the material to which the button is secured, comprising two 55 relatively movable plates each provided with a projection for engaging in the eye of said shank, and means for holding said plates in closed engaging relation.

6. In combination with a button having the usual shank forming an eye, a securing device cooperating with said shank on the opposite side of the material to which said button is applied, comprising two semi-circular plates pivotally connected near one 65 end whereby they may be moved into partially overlapping relation, and having indentations formed in the adjacent edges thereof in which said shank lies, and cooperating tongues extending between said indentations 70 and projecting in the eye of the shank, during such overlapping relation, and means near their opposite ends for holding said plates in overlapping relation in engagement with said shank. 75

7. In combination with a button having the usual shank forming an eye, a securing device cooperating with said shank on the opposite side of the material to which said button is applied, comprising two semi-circular plates pivotally connected near one end 80 whereby they may be moved into partially overlapping relation, and having indentations formed in the adjacent edges thereof in which said shank lies, and cooperating tongues extending between said indentations 85 and projecting in the eye of the shank, during such overlapping relation, and means near their opposite ends for holding said plates in overlapping relation in engagement 90 with said shank, said last mentioned means comprising a projection on one plate adapted to engage a recess on the other.

Signed at New York, New York, this 29 day of March, 1927.

MENDEL KAPILIAN.
